UNITED STATES PATENT OFFICE.

GEORGE E. SEIDEL, OF RICHMOND, INDIANA.

VEHICLE-TOP.

1,140,404.

Specification of Letters Patent. Patented May 25, 1915.

Application filed April 20, 1914. Serial No. 833,032.

To all whom it may concern:

Be it known that I, GEORGE E. SEIDEL, a citizen of the United States, residing in the city of Richmond, in the county of Wayne 5 and State of Indiana, have invented certain new and useful Improvements in Vehicle-Tops, of which the following is a full, clear, and exact specification, the same being such as will enable others to make and use the 10 same with exactitude.

My present invention relates to certain new and useful improvements in vehicle-tops, whereby the interior thereof may be absolutely inclosed against inclemencies of 15 the weather, with means whereby access and egress may be had in a minimum of time, and whereby such means is provided by a simple and easily operated construction.

The object of my present invention, 20 broadly speaking, is to provide improvements in vehicle-tops which will be strong and durable in construction, easily operated and controlled, artistic and attractive in appearance, and which can be manufactured 25 and sold at a comparatively low price.

More particularly stated, my object is, in connection with vehicle tops, to provide upwardly and downwardly slidable flexible doors, for the doorways, with channels in 30 which the doors are caused to travel, and with pockets or compartments in the roof of the top for the said doors, there being a separate pocket for each door with no communication therebetween, whereby when the 35 two doors are open, resting one above the other, it will be impossible for them to rub together or to become entangled with each other when being opened and closed.

Other objects and particular advantages 40 and improvements in my invention will be brought out in the course of the following specification, and the same is shown in the accompanying drawings.

The preferred means for carrying out my 45 invention in a practical manner is shown in the accompanying drawings, in which—

Figure 1 is a cross section elevation of 50 my vehicle top constructed, in accordance with the objects of my invention. Fig. 2 is a detail longitudinal section, as taken on the line 2—2 of Fig. 1, but showing in addition the trimmings in position. Fig. 3 is a per-

spective view of the framework, and showing the doors in operative position. Fig. 4 is a perspective detail view of the lower 55 portion of one of the bows, showing the manner of forming the channels for the doors. Fig. 5 is a detail perspective view of a portion of one of the doors alone. And Fig. 6 is a detail cross section, taken on line 60 6—6 of Fig. 3.

Similar indices denote like parts throughout the several views.

In order that the construction, the operation, and the advantages of my invention 65 may be better understood I will now take up a detailed description thereof in which I will set forth the invention as briefly and as comprehensively as I may.

Referring now to the drawings in detail, 70 letter A denotes the body, or bed, of a vehicle, and B denotes the seat of a vehicle, the seat extends across the central portion of and above the bed. Extending up from the forward corners of the bed A are the two 75 members, 1 and 2, of the front bow, each of the said members extends inward, horizontally, at the top, with their horizontal portions overlapping each other, with the ends of each extending across to the vertical portion of the other, substantially as shown in Fig. 3. Extending up from the central portion of the bed A are the two members 3 and 80 4 of the intermediate bow, each of the said members extends inward horizontally at the 85 top, with their horizontal portions overlapping each other, with the end of each extending across to near the vertical portion of the other, substantially as shown in Fig. 3. From the above it will be seen that the two 90 members 1 and 2 form the front bow, while the members 3 and 4 form the intermediate bow. It is of course to be understood that other bows, or ordinary construction, are to be employed, as for instance the bow C, but 95 with these this invention is not particularly concerned, except incidentally it might be stated that the bow C is slightly higher than the other bows mentioned, in order to give the proper slope to the roof.

Formed in the inner rear corners of the members 1 and 2, and in the inner forward corners of the members 3 and 4, are rabbets 5, 6, 7 and 8, respectively, for the pur-

pose hereinafter appearing. Secured to the inner faces of the members 1, 2, 3 and 4, and extending longitudinally thereof, are the respective metal strips 9, 10, 11 and 12, by which the said respective rabbets are formed into channels. The channels of the members 1 and 2 being open rearwardly, and those of the members 3 and 4 being open forwardly. The lower ends of each of the said channels are closed at *a*, as shown in Fig. 4, to form stops to limit the downward movements of the doors. The upper, far ends, of the said channels are closed, each by a stop *b*, as shown in Fig. 1, to limit the upward movements of the doors.

Numeral 13 indicates a thin impervious partition, which is preferably formed of sheet metal, the front and rear edges thereof being rigidly secured between the overlapping horizontal portions of the front and the intermediate bows, by means of bolts, screws, or the like, as indicated by letters *x* and *y*, and with which the members of the front and the intermediate bows, respectively, are secured together throughout the extent of the overlapping portions, substantially as indicated in Fig. 3. Located over the framework of the top is the roof or covering 14, which is usually formed of a waterproof fabric or other pliable material, the same being secured over the central portions of the bows, projecting over the member 2 and, in this instance, resting on the bow C, although it may rest on the bow 4, without interfering with the operation of this invention.

Numeral 15 denotes the lining of the top, which is usually of fabric, the same being attached to the under faces of the members 1 and 3 of the bows, in any well known manner.

From the above it will be observed that I provide a compartment between the roof 14 and the lining 15 which extends between the front and the intermediate bows. The said compartment is divided horizontally by the partition 13 into two pockets, *m* and *n*. In this instance, as is usual, two door openings are provided, one on each side of the top, the same being located between the front and the intermediate bows. In order to close the said door openings, when desired, two flexible doors are provided, one for each opening, the same being constructed substantially as shown in Fig. 5, and each comprises two flexible metal strips, 16 and 17, which are spaced apart and are located parallel with each other and they extend the full height of the doors. The strips 16 and 17 are connected at the bottom by the bar 18, and at various points thereabove by the rods 19, thereby forming the frame-work of the door, substantially as shown. Mounted in the framework of each door is the flexible textile or leather material, 20 and 21 respec-

tively, for the two doors. Located inward from, or behind, each of the strips 16 and 17 and parallel therewith, is a strip of webbing or the like, indicated by the numerals 22 and 23 respectively.

Each side edge of the material 20 and 21 is secured between a strip 16, or 17, and a strip of webbing, 22 or 23, where it is secured by the rivets or the like indicated by the letter *S*, as shown in Fig. 5, and by which a flexible metal strip, the edge of the material 20 or 21, and a strip of webbing are securely fastened together. The lower edges of the material 20 and 21 are each secured to its respective bar 18.

The width of the doors are such that their side edges will operate in the channels of the bows above referred to, as in Fig. 2. Located in each of the doors is a flexible transparency, forming the windows 24 and 25, which however may be variously changed. Secured to the central portion of the two bars 18 is an outside and an inside handhold, 26 and 27, respectively, by which the doors may be operated as desired.

From the foregoing it will be apparent that I provide a construction free from complications and parts which would be liable to get out of order or to become inoperative through wear or rough usage, and at the same time providing a construction which will be very effective in excluding wind, snow, rain, dust, or other inclemencies of the weather.

The features of this invention which I would particularly emphasize are: That each of the doors is provided with a separate pocket, each of which is entirely distinct from the other; the doors, when not in use, are entirely out of the way where they can not be seen and are fully protected from damage; the stops for positively limiting the upward and the downward movements of the doors; the means whereby the channels of the doors are formed; the means whereby the doors may be removed without danger of disfiguring any of the parts; and the various arrangements of the parts whereby the construction is formed into a unitary arrangement.

Having now fully shown and described my invention, what I claim and desire to secure by Letters Patent of the United States, is—

A vehicle top comprising a pair of spaced supporting bows adapted to be placed upon a vehicle body, each bow comprising two separable members, each member being L-shaped in cross section and having a vertical and horizontal portion, a plate secured to the short arm of the L of each member and extending parallel with the long arm of the L to form a guide channel, the horizontal portions of the members of each bow overlapping one another and being secured

together, a partition connecting the bows and having its opposite ends connected to the horizontal portions of the members, flexible curtains adapted to travel in said channel guides and the opposite ends of said members of each bow being bent inwardly to close the ends of the channel guides substantially as described.

In testimony whereof I have hereunto subscribed my name to this specification in the presence of two subscribing witnesses.

GEORGE E. SEIDEL.
